L. G. COPEMAN.
ADJUSTABLE THERMOSTAT.
APPLICATION FILED JULY 29, 1916.

Attorneys

UNITED STATES PATENT OFFICE.

LLOYD GROFF COPEMAN, OF FLINT, MICHIGAN, ASSIGNOR TO COPEMAN ELECTRIC STOVE COMPANY, OF FLINT, MICHIGAN, A CORPORATION OF MICHIGAN.

ADJUSTABLE THERMOSTAT.

1,349,364.

Specification of Letters Patent. Patented Aug. 10, 1920.

Application filed July 29, 1916. Serial No. 112,173.

To all whom it may concern:

Be it known that I, LLOYD GROFF COPEMAN, a citizen of the United States of America, residing at Flint, in the county of

5 Genesee and State of Michigan, have invented certain new and useful Improvements in Adjustable Thermostats, of which the following is a specification, reference being had therein to the accompanying drawings.

10 This invention relates to thermostats and refers more particularly to a thermostat adapted to automatically control the temperature of an electric stove or oven, although the invention in its broader aspects is not limited to the particular use specified.

15 Among the objects of the invention are to provide a thermostat which can be adjusted without completely disassembling the same; to provide a construction in which the thermostats attached to the various stoves can be adjusted to have substantially the same temperature readings; to provide a construction in which the circuit is closed 20 through an adjustable hand and a movable hand so arranged as to permit the hands to pass each other when a predetermined temperature is reached, thus avoiding any strain on the mechanism; to provide a construction in which the thermostat can be readily attached to the door or other part 25 of the stove without the necessity of exactly lining up the parts; to provide a construction in which the necessity of insulation between the metal flange of the thermostat and the metal part of the door is avoided; to provide a construction in which the adjustment of the expansion strip is controlled 30 by a cap screw which extends to the outside of the thermostat; to provide a thermostat of the character above referred to which can be easily and accurately adjusted; and in general to provide a new and improved construction of thermostat.

35 The invention also resides in such features of construction and arrangements and combinations of parts as will more fully hereinafter appear.

In the drawings:

40 Figure 1 is a front elevation of a thermostat embodying my invention;

Fig. 2 is a side elevational view;

Fig. 3 is a cross section on the line $x-x$ of Fig. 2;

Fig. 4 is a cross section on the line $y-y$ of Fig. 3;

Fig. 5 is a cross section on the line $z-z$ of Fig. 1.

Describing in detail the construction shown in the drawings, A designates the door lining and B the flange of the thermostat casing. This flange is carried by the outside shell C which shell at its front end is provided with the usual mica disk D through which the dial E of the thermostat can be observed. An indicating segment F is arranged on the dial as shown in Fig. 1, across which move the ends of the hands G and H.

These hands carry coöperating electrical contacts G' and H', the construction being such that the hand G can be adjustably set at whatever point along the dial that will permit the contact H' on the hand H to contact with the point G' on the hand G when the oven reaches the desired temperature. When the circuit is thus completed the source of current to the oven or other device controlled by the thermostat would be automatically shut off; the detailed construction of such circuit, however, forms no part of the present invention.

In actual practice it is found, there is a considerable amount of heat in the oven which does not affect the thermostat until a few moments after the circuit is disconnected. Where the hands are not allowed to pass each other this places a considerable strain on the mechanism, often injuring the thermostat or rendering it inaccurate. In the present construction this objection is avoided by so constructing the contact points that they will make contact at the desired temperature but will allow the movable hand to pass over the set hand in case the temperature rises after the contact has been made. Thus as shown in Fig. 5, the contacts G' and H' are rounded and so arranged that while they complete the circuit when in registration there is nothing but slight frictional resistance to prevent the movable hand passing over the stationary or set hand.

By setting the stationary hand G at any desired point, the thermostat can be set to shut off the current when any desired temperature is reached, this stationary hand being mounted on a shaft G² which is operated from the front of the casing by a button G³,

The movable hand H is automatically adjusted by the expansion of the bimetallic strip J. Thus when the temperature increases sufficiently to expand the strip J, it 5 will rock the movable hand until the contacts G' and H' engage and shut off the current to the stove. The strip J is secured at one end to an adjustable retainer strip K while its opposite or free end is connected to a link K', 10 the other end of which is secured to a cam or rock arm L on the shaft L'. The latter is rotatably mounted in a bearing L² and carries the movable hand H, there being a suitable stop L⁴ for limiting the movement 15 of the expansion strip.

Heretofore it has been necessary after the thermostats have once been tested and adjusted, to subsequently adjust by bending the expansion strip so as to relieve or increase 20 the tension of the strip. Therefore after the thermostat was installed in the door, further adjustment was impossible without completely disassembling the thermostat for readjustment. In the present 25 construction this objection is not only overcome but the adjustment can be made from a point exterior of the casing.

As shown in detail in Fig. 3, the adjustable retainer strip to which the expansion 30 strip is secured has a set screw M projecting outward through an elongated slot M' in the casing. A suitable lock washer N, and brass and mica washers N' and N² are provided, the arrangement being such that the set 35 screw M can be loosened and the retainer strip shifted around the casing to place the desired strain on the expansion strip, after which the set screw is tightened up to lock the retainer strip in at the adjusted position. By this arrangement it is possible to 40 adjust the various thermostats after they are in place so that the temperature readings for the various thermostats will be uniform. The amount of adjustment forward 45 and backward for the movable piece, or retainer strip M is sufficient to permit any desired adjustment within a range of over 200° of heat.

The operating or interior mechanism is 50 carried by a retainer ring O which is insulated from the shell or casing C by suitable mica insulation O'. The ring O has an elongated slot K² cut therein, to receive the strip K, the circumferential length of the slot K² 55 being greater than that of the strip K to permit of the adjusting movement described above. This operating or interior mechanism acts as one pole for the circuit to the hands, while the hand G acts as the other 60 pole. The lead to the hand G is through the brass terminal strip P which extends through an opening P' in the shell C, and is insulated therefrom by insulator strips P², while the lead to the other pole is through 65 a post Q extending through and insulated

from the shell. This arrangement whereby the shell and its base flange are insulated from the circuit, avoids the necessity of insulation between the flange of the thermostat and the metal part of the door. It will 70 also be noticed that the bottom of the shell C is cut away which allows a better transmission of heat from the oven to the thermostatic strip J.

In securing the base flange to the door or other support, I preferably employ an arrangement which will permit the base of the thermostat to be secured to the door, even if all the parts do not happen to exactly line up. For this purpose the flange B is provided with projections R and R' which have apertures S and S' of considerably greater size than the diameter of the screws T and T'. Adjusting plates U and U' are fastened to the projections R and R' by 80 securing members U² and U³, these adjusting plates being screw threaded and acting as a nut for the screws T and T'. As the front of the thermostat is sometimes covered by an escutcheon which is also held in 85 permanent position by screws, it has heretofore been impossible to get the escutcheon in place without practically disassembling the door for realinement. In the present construction the thermostat can be fastened 90 to the door and the screws T and T' left somewhat loose so as to permit the thermostat to be moved in any direction to line the base up correctly with the escutcheon, after which the screws can be tightened up 95 from the inside of the oven.

A thermostat constructed as above described can be more conveniently attached to its support than previous thermostats of this type, and the tension of the expansion 105 strip accurately adjusted without disassembling the thermostat. The invention, however, is not limited to the particular constructions shown for obtaining these advantages except as specified in the appended claims.

What I claim as my invention is:

1. In a thermostatic circuit-closing device, the combination with a casing, of mechanism within the casing comprising a 115 ring co-axial with said casing, thermostatic means in said casing, a pointer actuated by said thermostatic means and adapted to act as one of the terminals of an electric circuit, adjustable supporting means for said thermostatic means, insulation between said ring and said casing, a manually adjustable arm co-operating with said pointer and adapted to act as the other terminal of an electric circuit, and insulation between said 120 arm and said casing.

2. In a thermostatic circuit-closing device the combination with a casing and a dial therein, of a ring mounted in said casing and co-axial therewith, insulation be- 130

tween said ring and said casing, a bracket carried by said ring, a shaft carried by said bracket parallel to the axis of the casing, a pointer carried by said shaft adapted to travel over said dial, thermostatic means located within said ring for causing a turning movement of said shaft and pointer, a supporting member for the thermostatic means located within said casing, insulated 5 therefrom and circumferentially adjustable therein, an adjusting member extending through said casing for adjusting said supporting member, a manually adjustable arm coöoperating with said movable pointer to 10 close an electric circuit under predetermined temperature conditions, and insulation between said arm and said casing.

3. In a thermostatic circuit-closing device, the combination with a casing, a dial 15 therein, a ring mounted in said casing coaxial therewith and adapted to form one

terminal of an electric circuit, and insulation between said ring and said casing, of a terminal member adapted to form the other terminal of an electric circuit, insulation 25 between said terminal member and said casing, a manually adjustable arm located within said casing and connected to said terminal member, thermostatic means in said casing, adjustable supporting means 30 for said thermostatic means, and a pointer actuated by said thermostatic means and coöperating with said manually adjustable arm to close an electric circuit at a predetermined temperature. 35

In testimony whereof I affix my signature in the presence of two witnesses.

LLOYD GROFF COPEMAN.
